HIS ATTORNEYS

UNITED STATES PATENT OFFICE.

HERMAN C. HEATON, OF BERWYN, ILLINOIS.

CONDENSER.

1,232,304.

Specification of Letters Patent.

Patented July 3, 1917.

Application filed October 20, 1915. Serial No. 56,821.

To all whom it may concern:

Be it known that I, HERMAN C. HEATON, a citizen of the United States, residing at Berwyn, in the county of Cook and State 5 of Illinois, have invented an Improvement in Condensers, of which the following is a specification.

This invention relates to condensers and particularly to surface condensers employed 10 in steam condensing plants.

Heretofore, as commonly constructed, these surface condensers comprised a shell in which banks of tubes are placed, together with water boxes, in one of which there is an 15 inlet connection and also an outlet connection, in order that the circulating water may be forced into and through the tubes, preferably passing through the lower banks of tubes in one direction and through the other bank 20 of tubes in the opposite direction, in order to condense the steam which comes into contact with the outer surface of the tubes, upon being admitted to the interior of the condenser shell.

25 In this type of condenser, as thus constructed, it is necessary, in cleaning the tubes, to remove the condenser entirely from the service and the object of my invention is the provision of a surface condenser in 30 which the water boxes are so constructed that any predetermined bank or banks of tubes may be shut off so that the tubes may be cleaned or any tube or tubes temporarily plugged, and other repairs made without 35 taking the condenser out of service.

In the condenser made in accordance with my invention, the water box at the front end is divided into a plurality of compartments, arranged in pairs and each compartment 40 of every pair provided with means at the inlet or outlet side thereof for shutting off the circulating water, and at the opposite or rear end of the condenser I provide a water box divided into compartments each 45 of which corresponds with a pair of compartments in the water box at the head of the condenser so that the covers provided for each pair of compartments in the water box at the head of the condenser may be 50 removed after the circulating water has been shut off from these compartments in order that the tubes in the corresponding banks thereof may be cleaned or repaired as may be necessary.

55 In the drawing, Figure 1 is an end elevation and partial cross section of the front

water box of a condenser made in accordance with my invention,

Fig. 2 is a partial section and longitudinal elevation of the condenser, and 60

Fig. 3, is an end elevation and partial cross section similar to Fig. 1, showing the water box at the rear end of the condenser.

Referring to the drawing, the condenser made in accordance with this invention comprises a shell 10, of any desired configuration, as is usual in surface condensers. This shell, at its opposite ends, one of which is shown in the drawing, is provided with flanges 11, adapted to abut against tube 65 plates 12. Connected in and extending between the same and through the shell or body of the condenser there are banks of tubes 13. 14 designates the water box at the front end of the condenser. 70

At one side this water box is provided with a boss 15, corresponding in width with the width of the flange 11, and also adapted to abut against the adjacent tube plate 12, on the opposite side thereof, as clearly 75 shown in Fig. 2, these parts of the condenser being connected by bolts, or otherwise, with intervening gaskets, as is customary.

At one side, the water box 14 is provided 80 with an inlet 16 for the circulating water, and at the opposite side, with an outlet 17 for the circulating water.

Centrally the water box is provided with a partition wall 18 extending entirely across 85 the condenser, and extending from which, in suitable positions, there are partition walls 19 dividing the interior of the water box between the inlet and outlet connections into a plurality of compartments 20, 90 arranged in pairs, as indicated in Fig. 1, the lower compartment of each pair being the inlet compartment, and the upper compartment the outlet compartment for the circulating water. 95

100 Each pair of these compartments is provided with a cover 21 preferably having one or more hand holes fitted with hand hole covers 22, the covers 21 being suitably connected to the outer side of the water box 105 covers with intervening gaskets so as to make water tight joints.

At the inlet and also at the outlet end of each of these compartments in the water box, the same is provided with a device to shut off the circulating water, and inasmuch as the devices employed for each compartment 110

of the water box is the same but one of these will be described.

At the end of each compartment, the same is flanged, as indicated at 23, and fitted with 5 a slide plate 24, which is suitably secured in position, so that each valve will be tight against pressure from both sides.

A gate or other valve 25, of sufficient dimensions to close the inlet or outlet to the 10 compartment with which it is employed, is placed to move between the flange 23 and the slide plate 24, each gate valve being provided on its outer side with longitudinal ribs 26 and a cross rib 27.

15 Exterioly, the water box, both at the inlet and outlet sides thereof, is provided with apertured bosses 28, corresponding in number to the number of compartments into which the interior of the water box is divided. Secured to and extending from each apertured boss 28 is a valve sleeve 29, and secured at the outer end of the valve sleeve is a stuffing box 30.

Each gate valve 25 is provided with a 25 valve rod or stem 31, screw threaded at its inner end and adapted to pass through a tapped opening in the rib 27 in the gate valve with which the rod is employed. The rod also extends through the corresponding 30 valve sleeve 29, and through its stuffing box 30, and at its outer end is provided with a hand wheel 32, by which, as will be understood, the rod may be turned to move the gate valve 25 to or from the position shown 35 in Fig. 2. Any suitable indicator may be employed with each valve to show its exact position.

It will be understood that the position of the valve, as shown in Fig. 2, is the same 40 as that in which the corresponding compartment is shut off, that is to say, the position in which the circulating water is not permitted to flow through the bank of tubes corresponding to this compartment, and the 45 dotted line position wherein the gate valve lies within the sleeve 29 and the apertured boss 28, is the position in which the circulating water is permitted to flow through its bank of tubes.

50 Referring to Fig. 3, it will be seen that the water box applied at the rear end of the condenser is provided with partitions 33 dividing the same into compartments 34, each of which corresponds to a pair of the 55 compartments 20 in the water box at the head of the condenser. Each of the compartments 34 is provided with a cover plate 35 in which there are also hand holes provided with hand hole covers 36 similar to 60 the corresponding parts in the cover plates

for the water box at the head of the condenser. It will now be apparent that the water box at the rear of the condenser is similar to the one at the head of the condenser with the exception of being provided 65 with the transfer partition walls 18 and being fitted with the valves and means for operating the same to shut off the circulating water.

From the foregoing, it will be apparent 70 that by closing the gate valves to any pair of compartments, in the water box at the head of the condenser, the circulating water is shut off from these compartments, the corresponding compartment in the water box 75 at the rear of the condenser and the banks of tubes corresponding with these compartments so that these banks of tubes or any of the tubes therein may be cleaned or temporarily plugged without taking the condenser out of service.

I claim as my invention.

1. A condenser comprising a shell inclosing a unitary compartment, a tube plate at each end of said shell, tubes extending 85 through said compartment and secured in said tube plates, a water box secured to the tube plate at one end of said shell, partition walls dividing said water box into pairs of compartments, a cover plate for each pair of 90 said water box compartments, a water box at the other end of the condenser and provided with a plurality of compartments, each one of which corresponds to a pair of the aforesaid water box compartments, and devices 95 for shutting off the circulating water from any set of water box compartments and the tubes corresponding therewith.

2. A surface condenser comprising a shell, tube plates at the ends thereof, banks of 100 tubes secured at their ends in the said tube plates and extending through the said shell, a water box secured at one end of the said shell, partition walls dividing the said water box into pairs of compartments, a cover 105 plate for each pair of compartments, a slide plate secured at the outer end of each of said compartments, a gate valve movable therein, a rod associated with each gate valve, a wheel secured to each rod exteriorly 110 of the water box and by which the rod is turned to operate its gate valve, and a water box at the other end of the condenser provided with a plurality of compartments each one of which corresponds to a pair of the aforesaid water box compartments.

Signed by me this 18th day of September 1915.

HERMAN C. HEATON.
